UNITED STATES PATENT OFFICE.

GEORGE J. UFFELMAN, OF PITTSBURGH, PENNSYLVANIA, ASSIGNOR, BY DIRECT AND MESNE ASSIGNMENTS, OF TWO-FIFTHS TO PETER BISH AND NINE ONE-HUNDREDTHS TO EVERETT BOWMAN, BOTH OF PITTSBURGH, PENNSYLVANIA.

CURTAIN-POLE AND SHADE-ROLLER FIXTURE.

1,116,173.

Specification of Letters Patent.

Patented Nov. 3, 1914.

Application filed February 3, 1914. Serial No. 816,303.

To all whom it may concern:

Be it known that I, GEORGE J. UFFELMAN, a citizen of the United States of America, residing at N. S., Pittsburgh, in the county 5 of Allegheny and State of Pennsylvania, have invented certain new and useful Improvements in Curtain-Pole and Shade-Roller Fixtures, of which the following is a specification, reference being had therein 10 to the accompanying drawing.

This invention relates to brackets for supporting curtain pole and shade roller fixtures, and has for its object to provide a device of such class, in a manner as herein 15 after set forth, with means capable of supporting the form of curtain pole fixtures now in general use, and further capable of adjustably supporting shade roller fixtures to provide for different lengths of shade 20 rollers.

Further objects of the invention are to provide a bracket for the purpose set forth, which is simple in its construction and arrangement, strong, durable, efficient and 25 convenient in its use, readily set up with respect to the window frame and inexpensive to manufacture.

With the foregoing and other objects in view, the invention consists of the novel 30 construction, combination and arrangement of parts as hereinafter more fully described and illustrated in the accompanying drawings, wherein is shown an embodiment of the invention, but it is to be understood 35 that changes, variations and modifications can be resorted to which come within the scope of the claims hereunto appended.

In describing the invention in detail, reference is had to the accompanying drawings, wherein like reference characters denote 40 corresponding parts throughout the several views, and in which:

Figure 1 is an elevation of the upper portion of a window frame showing the adaptation therewith of a pair of supporting brackets in accordance with this invention and further showing the adaptation of the brackets for supporting a curtain pole and shade roller. Fig. 2 is a front elevation, on 45 an enlarged scale, of a supporting bracket in accordance with this invention and further showing one end of a curtain pole connected thereto. Fig. 3 is a vertical sectional view of the bracket. Fig. 4 is an inverted

plan in longitudinal section, and Fig. 5 is 55 a vertical sectional view of the bracket showing the adaptation therewith of a modified form of curtain pole supporting fixture.

Referring to the drawings in detail, 7 denotes the upper portion of a window 60 frame, and mounted upon each upper corner of said frame is a supporting bracket in accordance with this invention, and said bracket consists of a base plate 8, having the top thereof formed with a rearwardly 65 extending flange 9, and its outer side with a rearwardly extending vertically disposed flange 10. The flange 9 is provided with a plurality of openings 11 for the passage of holdfast devices to engage in the top edge of 70 the frame 7 for securing the plate 8 to said frame. The flange 9, when the bracket is mounted in position, extends upon the top edge of the frame 7, while the flange 10 is positioned against the side edge of the frame 75 7 and said flange 10 is provided with a plurality of openings 12 for the passage of holdfast devices to secure said flange 10 to the window frame. The plate 8 in proximity to the flange 10 is formed with a vertically 80 disposed slot 13.

The plate 8 at its bottom, is formed with a pair of outwardly projecting apertured ears 14-15 and mounted in the said ears is a threaded member 16, which has a head 85 at one side end as at 17, and at its other end has fixedly secured thereto a thumb piece 18. The head 17 abuts against the outer face of the ear 15, while the thumb piece 18 is arranged exteriorly of the ear 14. The 90 member 16 projects from the ear 14 a sufficient distance so as to receive the thumb piece 18. The member 16 is rotatably mounted in the ears 14-15 and supports a shade roller fixture 19, the latter being provided 95 with a squared upper portion 20 which abuts against the plate 8, and said fixture furthermore is provided with an opening 21, the wall of which is threaded and engages with the threads of the member 16. 100 In view of the fact that the member 19 abuts against the plate 8, which prevents turning of said fixture upon the member 16, it is obvious that when the member 16 is rotated, the fixture 19 will be shifted between the 105 ears 14-15, the direction in which the fixture 19 moves, depending in what direction the member 16 is rotated.

Arranged against the outer face of the plate 8 and above the ear 14, is a narrow plate 22, formed with a vertically disposed slot 23, which registers with the slot 13. The 5 plate 22, at its top, is provided with a rearwardly extending flange 24 which is seated upon the flange 9, and the said plate 22 is furthermore provided with a rearwardly extending flange 25, which is positioned against 10 the flange 10. The flanges 24—25 are provided with openings, and the holdfast devices which are employed for securing the plate 8 to the window are also employed for securing the plate 22 to the plate 8.

15 The plate 8 near its lower end is provided with an opening 26 and which registers with an opening 27 formed in the plate 22 and extending through the opening 27 is a stationary threaded member 28, the latter having a head 28^a which is seated in the opening 26, the latter being larger than the opening 27. Extending through and vertically shiftable in the slot 23 is a threaded member 29 which has its inner end provided with a 25 head 30 arranged in the slot 13. The slot 23 is of less width than the slot 13. When the plate 22 is secured in position with respect to the plate 8, the said plate 22 couples the members 28 and 29 to the plate 8, due to the 30 fact that the heads 28^a and 30 engage the inner face of the plate 22.

The members 28 and 29 are employed for detachably securing different sizes of curtain pole fixtures to the bracket and which 35 can be accomplished by adjusting the member 29 toward or away from the member 28, depending upon the distance between the openings in the curtain pole fixture through which extends the members 28 and 29 to secure 40 the fixture in position. The member 28 is stationary and extends through the lower portion of the curtain pole fixture 31 as illustrated in Fig. 2, or the lower portion of the curtain pole fixture 32, as illustrated in 45 Fig. 5. In Fig. 2 the member 29 has been adjusted to extend through the upper portion of the fixture 31, the latter being of less height than the fixture 32, whereas in Fig. 5 the member 29 has been adjusted to near 50 the upper ends of the slots 13 and 23 to extend through the upper portion of the fixture 32. The curtain pole fixture, when mounted upon the members 28 and 29, are secured to the bracket through the medium of nuts 33 55 which are mounted upon the members 28—29.

What I claim is:

1. A supporting bracket for curtain pole and shade roller fixture comprising a plate 60 adapted to be secured to a window frame and provided with a vertically disposed slot

and an opening below said slot, a member connected to said plate and provided with a slot and an opening registering respectively with the slot and opening of the plate, the slot of said member being of less width than the slot of the plate and the opening in said member being smaller than the opening in the plate, a stationary threaded member mounted in the opening of the plate and extending through the opening of said member, and a vertically adjustable threaded member seated in the slot of the plate and extending through the slot of said member. 65 70 75

2. A supporting bracket for curtain pole and shade roller fixture comprising a plate adapted to be secured to a window frame and provided with a vertically disposed slot and an opening below said slot, a member connected to said plate and provided with a slot and an opening registering respectively with the slot and opening of the plate, the slot of said member being of less width than the slot of the plate and the opening in said member being smaller than the opening in the plate, a stationary threaded member mounted in the opening of the plate and extending through the opening of said member, and a vertically adjustable threaded member seated in the slot of the plate and extending through the slot of said member, a pair of ears projecting from said plate, a rotatable threaded member mounted in said ears. 80 85 90

3. A supporting bracket for curtain pole and shade roller fixture comprising a plate adapted to be secured to a window frame and provided with a vertically disposed slot and an opening below said slot, a member connected to said plate and provided with a slot and an opening registering respectively with the slot and opening of the plate, the slot of said member being of less width than the slot of the plate, and the opening in said member being smaller than the opening in the plate, a stationary threaded member mounted in the opening of the plate and extending through the opening of said member, a vertically adjustable threaded member seated in the slot of the plate and extending 100 through the slot of said member, a pair of ears projecting from said plate, a rotatable threaded member mounted in said ears, and a fixture mounted upon and shifted by said adjustable member and normally abutting 105 110 115 against said plate.

In testimony whereof I affix my signature in the presence of two witnesses.

GEORGE J. UFFELMAN.
